UNITED STATES PATENT OFFICE.

STEPHEN MADJAR, OF OGDENSBURG, NEW JERSEY.

METALLIC RAILWAY-TIE AND RAIL-FASTENER.

1,247,124.

Specification of Letters Patent.

Patented Nov. 20, 1917.

Application filed June 8, 1917. Serial No. 173,458.

To all whom it may concern:

Be it known that I, STEPHEN MADJAR, a subject of the King of Hungary, residing at Ogdensburg, in the county of Sussex and State of New Jersey, have invented certain new and useful Improvements in Metallic Railway-Ties and Rail-Fasteners, of which the following is a specification.

This invention relates to certain new and useful improvements in metallic railway tie and rail fastener.

The primary object of the invention is the provision of a railway tie preferably formed of metal and adapted for mounting rails thereon in their operative positions, the rails being readily secured to the tie without the employment of screws or bolts and in a readily releasable manner.

A further object of the device is the provision of a metallic tie adapted for the seating reception of railway rails thereon, cooperating fasteners being detachably carried by the tie for removably retaining the rails in their operative positions.

A still further object of the device is the provision of a rail tie and fastener which is serviceable as a strengthening means for a rail joint, the engaging ends of the connected railway rails being positionable thereon in secured relations.

In the drawings forming a part of this application and in which like designating characters refer to corresponding parts throughout the several views:—

Figure 1 is a side elevation of the present form of tie with two rails shown in transverse section secured thereon, one of the attaching members being illustrated by dotted lines in its released position.

Fig. 2 is a top plan view thereof.

Fig. 3 is a vertical longitudinal section through a portion of the same.

Figs. 4 and 5 are detail sectional views taken upon lines IV—IV and V—V respectively, of Fig. 3.

Fig. 6 is a perspective view of an end portion of the tie.

Fig. 7 is a perspective view of one of the locking housings employed.

Fig. 8 is an inverted perspective view thereof.

Fig. 9 is a perspective view of the locking key employed with the tie.

Fig. 10 is a perspective view of rails in connected arrangement serviceable with the present tie.

Fig. 11 is a transverse sectional view thereof, and,

Fig. 12 is a perspective view of an end portion of one of the rails.

The present invention resides in a tie 10 preferably formed of metal herein illustrated of solid formation, rectangular in cross-section, the same being adapted for mounting railway rails 11 operatively thereon and secured transversely thereof by a locking housing 12 and a key 13 which are arranged for each rail at points adjacent the opposite ends of the tie.

An inwardly-projecting flange 14 is arranged properly spaced from each end of the tie 12 upon the upper face 15 thereof for the reception of the outer base flange 16 of a rail when properly spaced apart the gage width of the road-bed.

Grooves 17 are provided at opposite sides near the upper edges of the tie 10 forming overlying ledges 18 which are provided with notches 19 therein opening at the top of the tie.

The housing 12 is of general channel shape and has its opposite sides 20 arranged with spaced inwardly projecting lugs 21 adapted for passing through the notches 19 and seating upon the bottoms 22 of the grooves 17, whereby the housing 12 may be moved outwardly toward the adjacent free end of the tie, thereby arranging the lugs 21 beneath the ledges 18. It will be noted that when the rail 11 is positioned upon the tie 10 with its outer base flange 16 beneath the flange 14 of the tie, the housing 12 is slidably moved toward the inner flange of the rail 11 for engaging the inner flange of the rail within the tapered recesses 23 formed in the outer end of the housing and whereby as will be evident, the rail 11 will be secured to the tie 10 until the housing 12 has been released by moving inwardly to the position illustrated by dotted lines in Fig. 1 of the drawings.

The key 13 is formed of slightly resilient material and has a tapered foot 24 at one end thereof for seating reception within a socket 25 in the inner end of a central slot 26 in the top plate 27 of the housing 12. A head 28 is provided at the other end of the key 13, which head is arranged within a notch 29 in the inner edge of the housing 12. The upper face of the key head 28 normally lies flush with the upper face of the housing, with the key resiliently positioned

therebeneath. The housing 12 is readily positioned upon the tie 10 in the manner shown by dotted lines in Fig. 1 and during the outward sliding movement of the housing toward the adjacent rail 11, the key 13 will be held within the slot 26 by riding upon the upper face of the tie 10; but when the housing reaches its operative position in engagement with the inner flange of the rail, 5 the heel 30 beneath the head 28 of the resilient key 13 drops within a keeper opening 31 at the inner end of a central groove 32 in the face of the tie, whereby the housing is locked in its operative position, as best illustrated in Figs. 3 and 5 of the drawings.

It will be understood that when it is desired to release the rail 11, the head 28 of the key 13 is elevated by any suitable tool, thereby releasing the heel 30 from the 10 keeper opening 31 and permitting the housing 12 to be slid inwardly disengaging the recesses 23 from the adjacent rail flange 16. A rail joint is preferably employed with this 15 form of tie of similar construction to that illustrated in Figs. 10, 11 and 12 of the drawings. The rail 11 is arranged with a suitable cut-away end portion 33 forming a tongue 34 while the adjacent end of the co-operating rail has a complementally formed 20 slotted end portion 35 for engaging therewith, a bolt 36 retaining the rail ends together. In this manner, the present form of rail joint consists in strengthening the 25 rail joint while side projections 37 may be arranged upon the base flanges 16 of the rails, suitably spaced apart for receiving the flanges 14 and the housings 12 therebeneath.

A serviceable construction is provided which possesses great strength and by means 30 of which rails may be easily secured to a tie and readily detached therefrom whenever desired without requiring the employment of any screws or bolts or other well-known fastening devices while the rails will not become released accidentally by reason of vibrations produced by the varying traffic 35 conditions.

What I claim as new is:—

1. A device of the class described comprising a metallic tie having grooves forming

ledges with spaces therebeneath, an inwardly projecting flange upon the said tie outwardly of said grooves adapted for engaging the outer base flange of a rail, a channel-shaped housing provided with 55 spaced inwardly projecting lugs adapted to overlie the tie with the said lugs passed through the said spaces, and positioned beneath the said ledges and slidably arranged upon the bottoms of said grooves, the said 60 housing having recesses in its outer end positioned opposite the said rail-engaging flange, and locking means for said housing.

2. A device of the class described comprising a metallic tie having grooves forming 65 ledges with spaces therebeneath, an inwardly projecting flange upon the said tie outwardly of said grooves adapted for engaging the outer base flange of a rail, a channel-shaped housing provided with 70 spaced inwardly projecting lugs adapted to overlie the tie with the said lugs passed through the said spaces and positioned beneath the said ledges and slidably arranged upon the bottoms of said grooves, the said 75 housing having recesses in its outer end positioned opposite the said rail-engaging flange, the said housing having a groove in the under face of the top plate thereof having a receiving socket at its inner end and 80 terminating in a notch in the said plate at the outer end of the slot, the tie being provided with a groove beneath the said housing terminating in a keeper opening at its inner end, and a resilient key having a tapered 85 foot arranged within said socket and a head within said notch and provided with a heel adapted for automatic engagement with the said keeper opening when the housing is in its operative position with a portion of said 90 key arranged within said groove.

3. A device of the class described comprising a tie, a rail-engaging transverse flange upon said tie, a housing adapted for spanning relation with respect to said tie adjacent said flange, bayonet slot connections between said housing and tie, and a releasable locking key for said housing.

In testimony whereof I affix my signature.

STEPHEN MADJAR.
